PAGE 2

FIG.2

FIG.3

FIG. 4

FIG. 5

Fig. 1 is a three-quarter view in perspective of a truck, embodying our new design;

Fig. 2 is a front elevation view;

Fig. 3 is a side elevation view;

Fig. 4 is an elevation view showing the other side of the truck; and

Fig. 5 is an elevation view showing the rear of the truck.

We claim:

The ornamental design for a truck, as shown.
